V. D. COGLON

ELECTRICAL INSECT DESTROYER

Filed Aug. 5, 1925

INVENTOR
VICTOR D. COGLON.
BY *Det. Herston Haugh Jr.*
ATT'YS.

UNITED STATES PATENT OFFICE.

VICTOR DENNIS COGLON, OF CALGARY, ALBERTA, CANADA.

ELECTRICAL INSECT DESTROYER.

Application filed August 5, 1925. Serial No. 48,331.

This invention relates to improvements in electrical insect destroyers and more particularly to devices of this description in the form of screen doors, and the objects of the invention are to provide a simple and durable device of this description which can be manufactured at low cost and placed on the market in large quantities.

With the foregoing and other objects in view, the invention consists essentially in a screen or the like comprising double screen sections, preferably of metal, including casings intermediately woven with a plurality of wires adapted to be rigidly secured to one another and having suitable insulating means therebetween, the wires being intermediately supported in said casings by spaced insulating bars or the like, and separate electrical means for connecting the wires in each section to the source of electrical power, whereby on an insect endeavouring to pass through said double screen it contacts with the wires in each section to close the circuit, thus being immediately electrocuted, and insulated means for securing the sections together.

Referring to the drawings, in which like characters of reference indicate corresponding parts in each figure;

Figure 1 is a plan view of a door partly broken away, with the top panel replaced by my improved screen;

Figure 2 is a perspective view, partly broken away, of my improved screen;

Figure 3 is a plan view showing the insulating plate between the sections.

Referring now more particularly to the drawings, A indicates my improved screen as a whole adapted to be used as a screen or fitted into a door, as illustrated in Figure 1, or in any other suitable and convenient manner for the purpose specified. This screen consists essentially of two frames 1 and 2 preferably of metal, and these sections in turn are provided with screening in the form of a plurality of wires 5 and 6 forming two distinct sets adapted to be separately connected through connections 12 with a source of electrical power. The frames 1 and 2 are duplicates of one another and are designed to be rigidly secured together by

means of rivets 4 extending through orifices 4^a therein registering with one another and provided with apertures 8 whereby the frame as a whole may be secured in position. 55 These rivets are suitably insulated, while between the sections is a sheet or plate 3 of insulating material. Intermediately arranged in spaced relationship to one another are a plurality of bars of insulating material 7 to support the sets of wires or screening 5 and 6.

It will be noted, as illustrated in Figure 2, that when the sections are secured together the individual wires of the different sets or screen carried thereby will be in staggered relationship to one another to more effectively ensure that an insect endeavouring to pass through the screens will contact immediately with one of the wires carried by each section. The wires are insulated and connected as at 12 to the different poles of a source of electric power so that being insulated from one another and each connected to one pole of a source of electricity, the circuit is not closed until the insect, endeavouring to pass through the screen, closes it and thus charges the wires.

From the foregoing, the simplicity and effectiveness of my device as compared with 80 electrical screens and electrical insect destroyers heretofore in use will be apparent.

As many changes could be made in the above construction and many apparently widely different embodiments of my invention, within the scope of the claims, could be constructed without departing from the spirit or scope thereof, it is intended that all matter contained in the accompanying specification and drawings shall be interpreted 85 as illustrative and not in a limiting sense. 90

What I claim as my invention is—

1. In an electric insect destroyer, a screen 95 formed of two separate casing sections provided with separate wiring and adapted to be rigidly secured together, a plate of insulating material adapted to fit between the sections, insulated means for securing the sections together, means for connecting the wires forming the screen portion of said sections separately to opposite poles of a source of electrical energy. 100

2. An electrical insect destroyer comprising a pair of duplicate metal casings provided with a plurality of wires therein adapted to form a screen, a sheet of insulating material adapted to fit between said sections and means through the sections for rigidly securing them together and separate wires connecting the first mentioned wires in each section to opposite poles of a source of

electric power whereby on an insect endeavouring to pass through the wires and contacting with the wires of each section the circuit is closed, and means for insulating the securing means.

In witness whereof I have hereunto set my hand.

VICTOR DENNIS COGLON.
